(57) **CLAIM**

We claim the design for a firearm receiver cover having an accessory mount, as shown and described in the following figures.

DESCRIPTION

FIG. 1 is a front view of a firearm receiver cover having an accessory mount.

FIG. 2 is a back view of the firearm receiver cover having an accessory mount of FIG. 1.

FIG. 3 is a view from the left of the firearm receiver cover having an accessory mount of FIG. 1.

FIG. 4 is a view from the right of the firearm receiver cover having an accessory mount of FIG. 1.

FIG. 5 is a view of the top of the firearm receiver cover having an accessory mount of FIG. 1.

FIG. 6 is a view of the bottom of the firearm receiver cover having an accessory mount of FIG. 1.

FIG. 7 is an oblique view from the top back left of the firearm receiver cover having an accessory mount of FIG. 1.

FIG. 8 is an oblique view from the top front right of the firearm receiver cover having an accessory mount of FIG. 1.

FIG. 9 is an oblique view from the bottom front left of the firearm receiver cover having an accessory mount of FIG. 1; and,

FIG. 10 is an oblique top right view of an AK47 firearm with the firearm receiver cover having an accessory mount of FIG. 1 installed. The AK 47 firearm is not part or the disclosed design.

Broken lines are for the sole purpose of illustrating the environment of the article only and form no part of the claimed design. The Figures are not necessarily drawn to the same scale.

The claimed subject matter is directed to a receiver cover for a rifle.

1 Claim, 10 Drawing Sheets
